UNITED STATES PATENT OFFICE.

CHARLES T. JOHNS, OF CLEVELAND, OHIO, ASSIGNOR OF ONE-HALF TO
CHARLES D. EVERETT, OF SAME PLACE.

RAILWAY SAFETY-SWITCH.

SPECIFICATION forming part of Letters Patent No. 274,200, dated March 20, 1883.

Application filed December 4, 1882. (No model.)

To all whom it may concern:

Be it known that I, CHARLES T. JOHNS, of Cleveland, in the county of Cuyahoga and State of Ohio, have invented a certain new and Improved Railway Safety-Switch; and I do hereby declare that the following is a full, clear, and complete description thereof.

This invention relates to a certain improved railway-switch, the nature of which consists in making the target standard or shaft in two sections, and so that one section thereof will have at one end a socket or sleeve to receive a stem projecting from the end of the other section and fitted or jointed together. The junction of the two sections is surrounded by a spiral spring, one end of which is attached to a lug projecting from the upper section of the standard, the other end of the said spring being connected to a lug projecting from the lower section of the standard, which admits of the sections moving jointly or separately, as required. The said standard is connected by suitable means to the switch-rails, so as to open and close the said switch, as necessary. By means of the jointed standard and spiral spring, in connection with the switch-rails, a train in passing over the switch when it is closed will open it, going through without danger of derailing the cars, and as soon as the train has passed through, the switch, by the action of the spring, is closed, thereby rendering it a safety-switch.

That the invention may be more fully understood, reference will be had to the following specifications, and to the annexed drawings, making part of the same, in which—

Figure 1 is a plan view; Fig. 2, a view of the frame and target-standard in vertical position. Fig. 3 is a view of a detached section of the standard, showing the jointed connection.

Like letters of reference refer to like parts in the several views.

For the purpose of showing the practical operation of the said improvement, reference will be had to the representation of a railway-track.

In Fig. 1, A A' is the main line, and B B the switch-rails, connected with the ties in the ordinary way. The switch-rails are connected

together by means of the bar C, to which is jointed the link D at E, at one end, the other end of the link being loosely connected to the wrist F, Figs. 2 and 3. This wrist is attached to the crank G, which forms a part of the lower section, H, of the target-shaft. The upper end of this section terminates in a round stem or tenon, I, Fig. 3, over which is movably fitted the socket J, which socket forms the lower end of the upper section, K, of the target shaft or standard L, Figs. 1 and 2. The lower section of the standard is journaled in the box M and the upper section in the box N, which boxes are attached to the stand or frame O, which supports the mechanism for operating the switch, which is actuated by means of the lever P, connected with the standard L, as seen in Figs. 1 and 2. On the under side of the lever P is a pin, which is made to enter some one of the holes in the segment Q, according to the position of the lever in opening and closing the switch-rails B B in their relation to the main or side tracks. The junction of the two sections K H is surrounded by a spiral spring, R, Fig. 2, the upper end of which is attached to the lug a, projecting from the section K. The lower end of the spring is secured to the lug b of the lower section. This spring is made of sufficient strength or force as not to yield or spring out in moving the switch-rails from one side to the other in switching, by turning the lever P to operate the switch-connections with the rails for ordinary use. The spring force is of that strength that the movement of the lever P will turn the two sections H and K jointly without the spring yielding, so that one section will not thus turn without moving the other. By this means the invention may be applied to all the ordinary uses of switching, with the additional advantage of being an automatic safety-switch, as will be seen.

In case a train is passing over the rails B' A to the line A² A³, with the switch-rails B B in the position shown in Fig. 1, it follows that in an ordinary switch in the position shown the wheels of the train upon one side would run off the rail B at the end c, and the wheels upon the other side would run in between the

switch-rail at d and the main rail A^2 . In this way the wheels on one side would be jammed in between the switch and main rails along the part $d\ e$, and on the other side the cars would be derailed, which would destroy the switch and cause more or less injury to the train. With my improvement the train would pass safely through without injury to it or the switch when misplaced, as seen in Fig. 1. As the train passes over the line $B'\ A$ to the line $A^2\ A^3$ the wheel-flanges, on entering between the switch and main rails at $d\ e$, by the great force and weight of the train, will force the switch and main rail at $d\ e$ apart and allow the wheels to pass through; at the same time the end of the switch-rail at e will be brought in contact with the main rail A^2 . In this way the train will safely pass through the misplaced switch from the line $B'\ A''$ to $A^2\ A^3$. The force of the spring will yield to the force of the passing train, and by the resiliency of the spring R the switch-rails will be forced or drawn back to the original position, (seen in Fig. 1,) which is right for a train passing from $A^2\ A^3$ to rails $A'\ A''$, but misplaced for a train running over $A\ B'$ to $A^2\ A^3$. At the time the switch-rails are in the position seen in Fig. 1 the lever P is locked or held in place by means of the pin f in the lever extending into the proper hole in the segment, as noted in Figs. 1 and 2, which prevents the upper section, K , of the standard L from turning in either direction; but at the same time the lower section, H , is allowed to move by the force of the train-wheels in passing through between main and switch rails, which overcomes the force of the spiral spring and opens the switch for the train to pass through in safety, as before stated, notwithstanding its misplacement. The distance between the tread of the rails at $e\ e$, Fig. 1, is less than at $A\ B'$. Hence the resistance of the rail along the line from A to A^3 with the action of the train will force the movable switch-rails from the rail at R to S , and the same result would ensue in case the switch-rails in misplacement were forced in the same way from

the fixed rail side at S to R . The reaction of the spring will force back the switch-rails to the same position as that before the train passed, as before mentioned. It will make no difference on which side of the main rails the switch may be displaced, the result being the same so far as the safety referred to is concerned, as the action of the spring in allowing the switch to open for a train when misplaced and its moving back to its former position is the same. 50 55

It is intended that the switch mechanism may be operated as ordinarily to run the train from one track to another. The improvement in the said switch mechanism is brought into 60 action automatically only, by the car-wheels, in case of displacement of the switch, as herein-before described.

The improvement may be readily applied to all stand or ground railway-switches, as usually constructed. 65

I am aware that sliding sectional switch-rods have been used with a coiled spring surrounding the same with the ends of the spring connected to each sliding link; but what distinguishes my invention is the construction and arrangement herein described and claimed. 70

What I claim as my invention, and desire to secure by Letters Patent, is—

1. In railway-switches, the standard L , in 75 two sections, jointed or movably connected together, in combination with the spiral spring surrounding said sections, with the ends thereof attached, respectively, to the said sections, substantially as described, and for the purpose 80 set forth.

2. The standard L , formed in two sections movably connected, together inclosed within a spiral spring connected with said sections, in combination with a railway-switch, substantially as and for the purpose specified. 85

In testimony whereof I affix my signature in presence of two witnesses.

CHARLES T. JOHNS.
